DESIGN FOR A REFRIGERATOR CABINET

Chester A. Frick, Muncie, Ind., assignor to Glasscock Brothers Mfg. Co., Muncie, Ind., a corporation of Indiana

Application August 17, 1936, Serial No. 64,432

Term of patent 7 years

To all whom it may concern:

Be it known that I, Chester A. Frick, a citizen of the United States, residing at Muncie, in the county of Delaware and State of Indiana, have invented a new, original, and ornamental Design for a Refrigerator Cabinet, of which the following is a specification, reference being had to the accompanying drawing, forming part thereof.

The figure is a perspective view of a refrigerator cabinet embodying my design, the side and end not shown being the same as the side and end illustrated.

I claim:

The ornamental design for a refrigerator cabinet, as shown and described.

CHESTER A. FRICK.
